UNITED STATES PATENT OFFICE

GERARD T. SEGE, OF REVERE, MASSACHUSETTS

COMBINATION LOADED SHOT SHELL

Application filed September 3, 1929. Serial No. 390,222.

This invention relates particularly to a loaded shot-shell, and has for its object the prevention of injury to the shot when fired, to introduce a new element in the load, which owing to its nature serves, as a seal to the powder charge, a gas check, a shock absorber, a cleanser of the bore of the gun, and in connection with the placing of an expandable shot case butted on it, admits the construction of an air chamber therein, which aids in the control of both, gas and recoil, another object is the lessening of recoil through the form used in securing the case in the shell and closing the ends of both, in a secure manner, a further advantage is due to the construction of the case, allowing the expansion and contraction in its form simultaneously when passing through the muzzle of the gun, another object is to insure the placing of the case in the shell, and shell in the gun, in a predetermined position.

In carrying out my invention, I use in its construction in addition to its usual elements, additional elements of matter, and new modifications as will appear in the drawings and numerals of reference.

In the drawings;

Fig. 1 is a longitudinal sectional view of a loaded shot-shell and case, constructed in accordance with my invention.

Fig. 2 is a perspective view of a cylindrical tube to form the shot case, also shows the lands inverted.

Fig. 3 is a longitudinal view of the case in process of construction with lands and cuts.

Fig. 4 is a longitudinal sectional view, of the case with lands and cuts when constructed.

Fig. 5 is a perspective view partly in section, of the shot case in a modified form, with the lands inverted.

Fig. 6 is a perspective view of the combination wad in the inner end of the shot case.

Fig. 7 is a perspective view in detail of the wad in combination wad and cap.

Fig. 8 is a perspective view in detail of the cap in combination wad and cap.

Fig. 9 is a perspective view of the combined wad and cap.

Fig. 10 is a longitudinal view of the shell completed.

In the drawings, the shell comprises the body 1 with head 2 and usual base 3 and primer 4. 5 designates the powder and 6 the powder wads. 7 designates the composition of matter, consisting of spermaceti $\frac{1}{16}$ " in depth. 8 designates the expandable shot case of cylindrical form, composed of paper, used paper shells preferred, but any paper tubing of cylindrical form, and equal tensile strength may be used, and as shown by Fig. 3 the lands 14 are formed when it is reformed into a cylindrical form, and the cuts 13a and 13b are cut in the lands 14 longitudinally, and the inner end crimped inwardly as shown particularly by Fig. 5 and its numerals of reference, it is then placed in the shell 1, with its lands lines 14 in alignment longitudinally with the mark 70 15 on the exterior of the shell 1, its inner combination wad 9a is then placed in position, thus forming an air chamber 10, as shown in the inner end of Fig. 5 the combination wad is formed of two members, 9a being 75 formed cylindrically of a slightly larger bore than the bore of the case, and is composed of adhesive paper tape, doubled, the 9b member is a modified form of less bore than the inner bore of the case sufficient to allow the outer ring of shot to extend down to the inner end of the case 8, the composition of this member 9b to be of felt, the shot charge 11, is then poured and lightly tamped into the shell and secured in place by the combination wad 12b, and cap 12a, both of cylindrical form, the cap 12a being composed of paper tape, doubled, and the 12b member of stiff cardboard paper, pressed firmly 80 into place with the index number 15 of the cap in line with the longitudinal number 15 on the shell 1, the numerals on the exterior surface of the shell 1, indicates the size of shot in the case, the shell is now placed in the gun, with its longitudinal lines on the perpendicular axis of the gun, thus assuring the opening of the sides of the case in a horizontal direction, and spreading the charge with a somewhat elongated major axis, thus 85 increasing the lead on passing objects. It 90 95 100

has been found by repeated trials that by thus placing the case in the shell and gun, the flight of the case was true toward the mark desired, and very uncertain, if placed otherwise. It is also obvious that by these forms of case construction, and the means employed in securing them in the shell that the utmost space possible for modification of the multiform charge of shot is secured, it has been found in practice that the length of the cuts in the lands, control the required range up to and beyond 100 yards. It is not known that a shot gun shell and case, having a plurality of elements therein, has ever been so marked on its exterior surface that the marks indicate the position of the case and its contents in the shell longitudinally, and also indicates the proper position of the shell in the gun, in relation to its perpendicular axis when in position for discharge.

In the modification of the expansible shot case as shown by Fig. 5 the inverted lands and cuts are designated by the letter C, and the shot case, is exactly similar in every particular with this exception; in practice the inverted lands case is best in full choke 70% or more; and the protuberant land case is best for a modified choke barrel.

The composition of matter (spermaceti) used in this load has a special significance as it has an affinity for the powder element used in the load of the shell.

The shell is first marked on its outside surface by the index marks as shown by the numeral 15, it is then charged with powder and wad, on the powder wad and against the inner walls of the shell the composition (spermaceti) is imposed while in liquid condition, the shot case 8 with its longitudinally disposed indentation 13, is then placed in position with its indented lines 13, in true alignment with the index lines 15, on the shell 1. The wads 9a and 9b are then placed in the bottom of the case, and the required charge of shot 11, is disposed in the case 8, and secured in the case 8 and shell 1 by the combination wad 12b and cap 12a and the shell 1 placed in the gun with the index lines 15 in true alignment with the perpendicular axis of the gun when in position for firing.

At the firing of the shell the spermaceti is crushed and powdered by the contra force exerted by the weight of the shot charge and restraint of the tightly secured wad 12b and cap 12a of the shell 1, the seal of the powder wad and against the wall of the shell is broken, the shot charge is settled and partially imbedded in the base and interior wall of the shot case without deformation, the recoil minimized, the top of cap 12a is severed from the shell, and the intense heat generated by the powder transforms the composition chemically into an active aid to the powder gases owing to its affinity therefor: The

shot case then passes through the cone, bore, and choke of the gun with its contents undeformed, and its velocity unimpaired.

Thus having described my invention what I claim as new and novel is:

1. In a shot shell comprising in combination a conventional powder wad, a layer of lubricating substance such as spermaceti imposed on said powder wad, a second wad on said layer of lubricating substance, a shot case disposed within the shell upon the second wad, said shot case having a plurality of longitudinally disposed indentations whereby said shot case is rendered somewhat elastic and a shot charge disposed in said shot case.

2. A shot shell as set forth in claim 1 wherein said shot case is open at its lower end and said second wad is provided with a stepped portion adapted to close the open end of the shot case when in position in the shell.

Signed at Revere, Massachusetts, this 24 day of August, 1929.

GERARD T. SEGEE.
